(57) **CLAIM**

The ornamental design for an electric blanket coupler, as shown and described.

DESCRIPTION

FIG. 1 is a front, top perspective view of an electric blanket coupler showing our new design.

FIG. 2 is a front view of an electric blanket coupler.

FIG. 3 is a rear view of an electric blanket coupler.

FIG. 4 is a left side view of an electric blanket coupler.

FIG. 5 is a right side view of an electric blanket coupler.

FIG. 6 is a bottom view of an electric blanket coupler.

FIG. 7 is a top view of an electric blanket coupler; and, FIG. 8 is a rear, bottom perspective view of an electric blanket coupler.

The broken lines in the drawing depict portions of the electric blanket coupler that form no part of the claimed design.
